CLAIM

The ornamental design for an ink tank for printer, as shown and described.

DESCRIPTION

FIG. 1 is a front perspective view of an ink tank for printer showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The features shown in broken lines in the drawings depict environmental subject matter only and form no part of the claimed design. The oblique shade lines in FIGS. 1 and 7 are intended to represent translucency.
